TEMPERATURE COMPENSATING
CONDENSERMelvin V. Weiss, Haddonfield, N. J., assignor to
Radio Condenser Company, Camden, N. J.

Application May 14, 1936, Serial No. 79,667

9 Claims. (Cl. 175—41.5)

This invention relates to a tuning condenser especially adapted for use in a superheterodyne type of radio receiver for use in aircraft work.

In radio receivers designed for aircraft, much attention must be given to the question of weight, without sacrificing mechanical strength and electrical stability.

Because of the dependence of aviation on radio signals, for directional beams, blind flying, reports and the like, it is extremely important that the airplane receiver, when tuned to a given frequency, does not drift out of tune. The problem of receiver drift is especially difficult in aircraft work because of the wide range of temperature encountered between ground level and high altitudes. Receiver drift is usually due to changes in the characteristics of the elements of the oscillator circuit, such as the tube, coil, resistors and more especially the tuning condenser because of its metallic structure expanding and contracting when subjected to these wide and many times rapid temperature changes, brought about by the aircraft work.

In a gang condenser, used in a superheterodyne aircraft receiver, the sections or units of the gang which tune the pre-amplifier circuits, variations in the capacity of these units, due to temperature changes, have the effect of reducing the overall sensitivity of the receiver but do not detune the receiver. Automatic volume control in the receiver will take care of the loss in sensitivity and maintain a constant audible output; whereas variations in the oscillator unit of the gang will detune the receiver.

It is therefore the principal object of my invention to provide a gang condenser for an aircraft receiver which, in general, has high rigidity but light weight, and one in which the oscillator unit is so constructed and arranged as to automatically compensate for a wide variation in temperature.

After much experimental work and many tests, I have found that by making the oscillator unit, and certain other parts of the gang condenser, out of a material having a substantially zero or 45 very low temperature coefficient, and arranging these in the manner to be hereinafter described, I can get an oscillator condenser which will automatically compensate for a wide change in temperature, and will attain the general object of my invention, as well as other ancillary objects which will occur to one skilled in this art, on a reading of the specification and accompanying drawing.

In the drawing:

Figure 1 is a plan view of a four-gang condenser in which my invention is incorporated, a small section of one end of the condenser being broken away.

Figure 2 is a part-vertical section and part-elevational view on the line of the operating shaft of Figure 1.

Figure 3 is a side elevation of the gang condenser shown in Figures 1 and 2, with certain parts at the drive end being broken away.

Figure 4 is a fragmentary end view of the drive end of the condenser.

Figure 5 is a perspective view of one of the condenser frame members.

Figure 6 is a perspective view of one type of support for the stator group of plates of one of the condenser units comprising the gang condenser.

Figure 7 is a perspective view of another type of support which may be used in place of the type of support shown in Figure 6.

In the various views, wherein like numbers refer to corresponding parts, 1 and 2 are the front and rear end plates of the frame of a gang condenser, four unit condensers being illustrated, 25 as A, B, C and D. The frame members 1 and 2 are rigidly held together by substantial aluminum rods 3 and 4, one of which is illustrated in perspective in Figure 5. The rods 3 and 4 are held to the end plate 2 through the medium 30 of grooves 5 which are adapted to receive slots in the end plate 2, all as defined in application Serial No. 724,688, filed May 9, 1934, by Stanley S. Cramer.

The rods 3 and 4 are further bound together 35 by shield and brace members 6, 7 and 8 fitting in cooperative grooves 9 in the rods 3 and 4 in a similar manner as described with respect to the end or rear bearing plate 2. Extending from the shield and brace plate 6 to the end plate 2, 40 on opposite sides of the gang condenser below the rods 3 and 4, are metallic bars 10 and 11, the plates 6, 7 and 8, and the end plate 2 being notched to snugly fit over these bars 10 and 11, and then afterwards, the metal at the junction 45 is upset so as to securely anchor the bars to the said plates or frame members.

Attached to the bars 10 and 11 in any satisfactory manner, as by rivets or screws 12, are insulators 13, to the upper portion of which are attached, as by screws 14, the tiebars carrying the stator groups of plates, all as set forth in Cramer Patent 1,800,719, issued April 14, 1931.

The rotor shaft is divided into two sections 15 and 16. The section 16, having a reduced end 55

17, is adapted to be force-fitted into the end of the section 15, which latter section carries the groups of rotor plates for the unit condensers A, B and C, while the section 16 carries the rotor plates for the unit condenser O, which illustrates an oscillator tuning condenser, whereas the unit condensers A, B and C are condensers for other tunable circuits associated with the oscillator unit. The stator group of plates of the oscillator unit O is carried on a pair of brackets 18 and 19, as shown in Figure 6, or on a pair of studs as shown in Figure 7, which are independent of the bars 10 and 11, as will be clear from Figure 1. When the brackets of Figure 6 are used, they are attached to the front end plate 1 by screws 20, preferably having large heads in order to get a large contact surface engagement with the plate 1. In the construction shown in Figure 7, the stud 30 has flat sides 31 to receive one end of an insulator 18 on one of these surfaces, the other end of the insulator being fastened to a stator tiebar. The stud 30 has an annular shoulder 32 to engage the rear side of the end plate 1, and an annular dowel or projection 33 of reduced diameter extending into the end plate 1. The washer 34 and screw 35 entering the said dowel and shoulder to hold the stud 30 securely in place on the end plate 1.

30 The rotor shaft is supported on the rear end plate 2 in any satisfactory manner as by a bushing 21 carried on a plate 22 fastened to the end plates in any satisfactory manner as by screws 23. The front end of the shaft is likewise supported in any satisfactory manner on the front plate 1, as by a bushing 20.

35 Fastened to the operating end 25, as by set screws 26, is a collar 27 carrying a spring 28 which continuously acts to force the rotor shaft toward the end plate 1. The usual rotor wipers are illustrated at 29.

40 Since this gang condenser is designed particularly for aircraft use, lightness is an essential feature; hence, the rods 3 and 4, together with the rotor shaft portion 15 and the plates of the units A, B and C, are made of aluminum. The shaft 16, with the extensions 17 and 25, together with the end plates 1 and 2, as well as the shield and support plates 6, 7 and 8, and the bracket supports 18 and 19, together with the rotor and stator plates for the oscillator condenser plates O are made of a material having a substantially zero temperature coefficient, such as a steel having a composition of nickel and iron, where the nickel may be of the order of 36%.

45 While the use of this special material in the places mentioned somewhat increases the weight of the gang condensers over what it would be if only aluminum were used, it, together with the construction described, eliminates expansion and contraction due to changes in temperature which would affect the operating characteristics of the oscillator unit. Since the stator plates, with their brackets shown in Figure 6, are carried on the mounting plate 1 and are all made of this special zero temperature coefficient material, these parts will not be affected by the temperatures ordinarily encountered by an airplane. If the changes in temperature are sufficient to affect the heavy frame members 3 and 4, causing them to expand longitudinally, this would carry the stator group of plates, with the end plate 1, in an endwise direction to the left, looking at Figure 1, but at the same time, the shaft 15 would also expand longitudinally and the spring

5 28 would carry the rotor shaft to the left along with and in substantially an equal amount with the stator plates, thereby keeping a substantially constant spacing between the stator and rotor plates. When these parts, that is, 3, 4 and 15, 5 contract, the operation or movement of the stator and rotor plates of the oscillator condenser is in reverse direction.

10 While I have shown a four-gang condenser, the number of units in the gang may be varied to suit requirements, but in any case, the temperature compensating oscillator unit is arranged to be at one end of the gang.

15 What I claim is:

1. In a gang condenser comprising a frame including end members and a unit condenser for tuning an oscillator circuit while the other units of the gang are used to tune amplifier circuits associated with the oscillator circuit, means for compensating in the oscillator unit for differences in temperature in which the condenser is used, said means including; unit plates, the stator plates of which are separately supported on one of said end frame members, the rotor shaft being in two parts operatively connected, said oscillator unit rotor plates being on one of said shaft portions, said stator and rotor unit plates, together with that part of the shaft carrying said rotor plates, the stator supports and at least the end frame member carrying said supports, all 30 being made of a material having substantially a zero temperature co-efficient, and means acting continuously on the gang rotor shaft to move it toward the end frame member carrying the said oscillator stator supports. 35

2. In a single-control gang condenser having an operating shaft, comprising a frame including end members for carrying rotor and stator group units of plates, the rotor plates being carried on said shaft one of said sets of group units 40 being adapted for use in tuning an oscillator circuit, while the other group units are used in other tunable circuits associated with the oscillator circuit, means for compensating in the oscillator unit for difference in temperature in which 45 the condenser is used, said means including stator and rotor plates for the oscillator unit made of material having a very low temperature co-efficient, and individual mounting studs for the oscillator stator plates attached to one end 50 frame member, all of the same kind of material as the unit plates, that part of the shaft for the oscillator rotor plates also being of the same kind of material as the unit plates, and means acting continuously on the gang rotor shaft to move it 55 toward the end frame member carrying the said oscillator stator supports.

3. In a gang condenser as set forth in claim 2, further characterized in that the said frame has, between said units, shield and brace members 60 which, with both end frame members carrying the entire rotor shaft, are made of very low temperature co-efficient material, the same as the oscillator unit plates.

4. In a gang condenser comprising a frame 65 including end members and a unit condenser for tuning an oscillator circuit while the other units of the gang are used to tune amplifier circuits associated with the oscillator circuit, means for compensating in the oscillator unit for differences in temperature in which the condenser is used, said means including; unit plates, the stator plates of which are separately supported on one of said end frame members, the rotor 70

75

shaft being in two parts force-fitted together, said oscillator unit rotor plates being on one of said shaft portions, the said end members being held together by a plurality of light-weight metallic members, while the rotor shaft for all the rotor plates in the amplifier condenser units is also of light-weight metallic material, while the stator with its supports and the rotor plates of the oscillator unit, together with both frame end plates, shield plates, rotor shaft portion carrying the rotor plates, are all made of a material having substantially a zero temperature co-efficient, and means acting continuously on the gang rotor shaft to move it toward the end frame member carrying the said oscillator stator supports.

5. In a gang condenser comprising a frame including end members and a unit condenser for tuning an oscillator circuit while the other units of the gang are used to tune amplifier circuits associated with the oscillator circuit, means for compensating in the oscillator unit for differences in temperature in which the condenser is used, said means including; a pair of independent supports for the stator plates of the oscillator unit, said supports being fastened to one end frame member, the frame end members being held together with a plurality of light-weight, rigid members, a rotor shaft for the gang, that part which carries the oscillator rotor plates, together with the rotor plates, the stator plates and their supports, and at least the end member carrying said supports, all being of a material having substantially a zero temperature co-efficient, and means acting continuously on the gang rotor shaft to move it toward the end frame member carrying the said oscillator stator supports.

6. In a gang condenser having stator and rotor plates, the rotor plates being carried on a rotor shaft and including an oscillator unit, means for compensating for changes in tempera-

ture to which it may be subjected in aircraft, said means including plates for the stator and rotor of said unit made of material having a very low temperature co-efficient, the stator plates having an independent metallic support of the same material, while at least that part of the rotor shaft carrying the unit rotor plate is also of the same material with means acting continuously on the gang rotor shaft to move it toward the end frame member carrying the said oscillator stator supports.

7. A gang condenser as set forth in claim 6, further characterized in that the supports for the rotor shaft at both ends, and the shield plates between units of the gang are of the same special material as the stator and rotor plates.

8. In a gang condenser for an aircraft radio receiver including, a frame carrying amplifier tuning units and an oscillator unit, means for preventing the oscillator unit of the gang from detuning the receiver because of changes in temperature to which the receiver may be subjected, said means including frame supports for the stator plates of the oscillator unit independent of the frame supports for the other units of the gang, a special shaft portion for the rotor plates of the oscillator unit; the stator and rotor plates of said unit, together with at least said stator frame supports and said special rotor shaft portion, all being made of a material having a very low temperature co-efficient, and means acting continuously on the gang rotor shaft to move it toward the end frame member carrying the said oscillator stator supports.

9. A gang condenser as set forth in claim 8, further characterized in that at least the end frame member carrying the special rotor shaft portion is made of the same kind of material as the oscillator unit plates.
